UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

PRESSURE-FLUID MOTOR

Application filed June 4, 1927, Serial No. 196,430. Renewed December 26, 1929.

This invention relates to pressure fluid motors and more particularly to pressure fluid motors of the hammer type.

An object of this invention is to provide an improved pressure fluid motor. A further object is to provide an improved pressure fluid motor of the hammer piston type wherein pressure fluid is supplied continuously to the front pressure area on the hammer piston and supplied periodically to the rear pressure area on the piston under the control of an automatic piston-controlled fluid distribution valve. A further object is to provide an improved pressure fluid motor wherein the fluid distribution means is extremely simplified and the power and efficiency of the motor is materially increased. These and other objects will, however, hereinafter more fully appear.

20 In the accompanying drawing there is shown for purposes of illustration one form which the invention may assume in practice.

In this drawing,—

25 Fig. 1 is a central longitudinally extending sectional view illustrating the improved pressure fluid motor.

Fig. 2 is an enlarged sectional view similar to Fig. 1 showing the valve and piston in different positions.

30 Fig. 3 is a transverse sectional view taken on line 3—3 of Fig. 1.

In this illustrative construction there is shown a pressure fluid motor of the hammer type comprising a cylinder 1 having a bore 2 in which a hammer piston 3 is reciprocably mounted. The hammer piston 3 has formed integral therewith and projecting forwardly therefrom a striking bar 4 movably mounted in a bore 5 formed within a front buffer ring 6. As shown, the cylinder 1 is provided with a forwardly projecting sleeve-like portion 7 having a bore 8 in which the buffer ring 6 is positioned. The rear end of the buffer ring 6 is seated against a shoulder 9 formed at the junction of the cylinder bore 2 and the bore 8, this buffer ring being held in position by a front chuck housing 10 projecting within the bore 8 and abutting against the forward end of the buffer ring. 50 The chuck housing 10 carries at the forward

end a usual chuck 11 within which a usual drill steel 12 is loosely mounted. Interposed between the buffer ring 6 and the chuck housing 10 is an expandable cup washer 13 engaging the periphery of the striking bar 4 and this cup washer prevents excessive leakage of pressure fluid from the cylinder bore past the striking bar. However, in case such leakage does occur the interior of the chuck housing 10 is vented to atmosphere through a suitable lateral opening 14. As shown, the rear end of the cylinder bore 2 is closed by a combined head block and valve chest 15 while engaging the outer surface of this head block is a rear plate 16. The chuck housing, buffer ring, cylinder, rear head block and rear plate are held in assembled relation in any suitable and convenient manner.

In the improved construction the valve chest 15 has formed therein alined bores 17 and 18 of different diameters and preferably having their axes alined with the longitudinal axis of the motor cylinder. Reciprocably mounted within the bores 17 and 18 is an automatic piston-controlled fluid distribution valve 19, herein preferably of the three spool differential type. The valve 19 is provided with a large rear end spool 20 fitting the bore 17 and a central spool 21 and a front end spool 22 both fitting the bore 18. As shown, the spools 20, 21 and 22 are connected by reduced portions 23 and 24. The outer end of the bore 17 is closed by the rear plate 16. Formed in the valve chest 15 at the forward end of the bore 17 and at the rear end of the bore 18 respectively are annular grooves or recesses 25 and 26, while located intermediate these grooves is a similar groove 27. Fluid pressure is adapted to be supplied to the motor through a longitudinal passage 28 communicating at 29 with the cylinder bore 2 at the forward end thereof. Leading from the supply passage 28 is a lateral passage 29^a communicating with the annular recess 25. As clearly shown in Fig. 3 the annular recess 26 is connected directly to atmosphere through radial passages 30. The intermediate recess 27 is connected to the rear end of the cylinder bore 2 through a series of passages 31. As shown, commun-

cating with the cylinder bore 2 intermediate the ends thereof as by a port 32 is a longitudinally extending throwing passage 33 which communicates with the bore 17 adjacent the 5 rear end thereof. Extending centrally through the valve 19 and communicating with the bore 17 is a restricted leak passage 34 which in turn communicates through a lateral port 35 with the bore 18 at a point 10 intermediate the spools 21 and 22.

In the operation of the improved pressure fluid motor it will be assumed that the hammer piston 3 is in the position shown in Fig. 1 and is about to be driven forwardly to effect 15 its working stroke. At this time, pressure fluid flows from the passage 28 through the lateral passage 29^a into the annular recess 25, through the bore 18, the annular recess 27 and thence through the passages 31 to the 20 rear end of the cylinder bore 2. Simultaneously, pressure fluid flows through the supply passage 28 through the lateral port 29 to the forward end of the cylinder bore, the fluid flowing from the forward end of the 25 cylinder bore through the port 32 and throwing passage 33 to the bore 17, and as a result the valve 19 is held in its forward position shown in Fig. 1. Due to the relatively larger 30 pressure area on the rear surface of the hammer piston the pressure acting on the relatively small front pressure area of the piston is overcome and consequently the hammer piston is driven forwardly. During this forward stroke of the piston the port 32 is cut 35 off by the piston head and the pressure within the bore 17 at the rear end of the valve leaks out through the passage 34, port 35, through the radial exhaust passages 30 directly to atmosphere. Continuous pressure 40 acting on the forward surface of the relatively large spool 20 causes the valve to be thrown rearwardly to the position shown in Fig. 2. The piston continues its forward travel due to the expansive action of the 45 pressure fluid and momentum and delivers a blow to the shank of the drill steel 12. When the valve assumes the position shown in Fig. 2 the pressure fluid in the rear end of the cylinder bore is exhausted to atmosphere 50 through the passages 31, annular recess 27, through the bore 18, annular recess 26 and passages 30 to atmosphere. The hammer piston is then driven rearwardly by the pressure fluid within the forward end of the cylinder bore acting continuously on the forward 55 pressure area of the hammer piston. As the piston 3 moves rearwardly the port 32 is again uncovered and pressure fluid is admitted through the throwing passage 33 and the valve is again thrown forwardly to the 60 position shown in Fig. 1 and this cycle of operation is repeated throughout the normal operation of the motor.

As a result of this invention an improved pressure fluid motor is provided wherein the

pressure fluid acts continuously on the forward pressure area of the piston while the pressure fluid is periodically supplied to act on the relatively large pressure area on the piston under the control of an automatic piston controlled valve. It will further be noted that an improved pressure fluid motor is provided wherein the fluid distribution means is exceedingly simplified and wherein the power and efficiency of the motor is materially increased. These and other advantages of this invention will be clearly apparent to those skilled in this art. 70 75

While I have in this application specifically described one form which my invention may assume in practice, it will be understood that this form of the same is shown for purposes of illustration and that the invention may be modified and embodied in various other forms without departing from its spirit or the scope of the appended claims. 80 85

What I claim as new and desire to secure by Letters Patent is:

1. A pressure fluid motor comprising a cylinder, a piston reciprocable therein, and fluid distribution means for effecting reciprocation of said piston including a passage for constantly admitting pressure fluid to the front end of said piston, means for controlling the supply and exhaust of fluid for the rear end of said piston comprising a reciprocable differential fluid distribution valve having a large spool and a reduced spool, a passage controlled by said piston for admitting pressure fluid from said cylinder to one surface of said large spool for throwing said valve in one direction to connect the rear end of said piston through the valve chest directly with the rear end of said first mentioned passage, and a passage for constantly admitting pressure fluid to the opposite surface of said large spool to throw said valve in the opposite direction to connect the rear end of said piston with the exhaust. 90 95 100 105

2. A pressure fluid motor comprising a cylinder, a piston reciprocable therein, and fluid distribution means for effecting reciprocation of said piston including means for constantly admitting pressure fluid to the front end of said piston, means for controlling the supply and exhaust of fluid for the rear end of said piston comprising a reciprocable differential fluid distribution valve having a large spool and a reduced spool, a passage controlled by said piston for admitting pressure fluid from said cylinder to one surface of said large spool for throwing said valve in one direction to connect the rear end of said piston with the fluid supply, a passage for constantly admitting pressure fluid to the opposite surface of said large spool to throw said valve in the opposite direction to connect the rear end of said piston with the exhaust, and a leak passage formed in said valve for connecting the pressure area at the 110 115 120 125 130 135

rear end of said large spool continuously with the exhaust.

3. A pressure fluid motor comprising a cylinder, a piston reciprocable therein and fluid distribution means for effecting reciprocation of said piston including means for constantly admitting pressure fluid to the front end of said piston, means for controlling the supply and exhaust of pressure fluid to the rear end of said piston comprising a reciprocable differential fluid distribution valve having a large end spool and reduced central and end spools, a passage opened by the piston on its rearward stroke for admitting pressure fluid from said cylinder to one surface of said large spool for throwing said valve in one direction, supply and exhaust passages controlled by said central spool, and means for constantly admitting pressure fluid to the opposite surface of said large spool for throwing the valve in the opposite direction.

4. In a drilling apparatus, a pressure fluid actuated percussive motor, a piston reciprocable therein, a striking bar projecting from the piston through one end of the cylinder, and fluid distribution means for actuating said piston including means for continuously admitting fluid pressure to the forward end of the cylinder to act on the reduced area of the piston around the striking bar, a valve for controlling the supply and exhaust of fluid to and from the rear end of the cylinder, said valve having a reduced spool for controlling the communication between the cylinder and the supply and exhaust, said valve also having a larger spool presenting an unbalanced area continuously subjected to fluid supply pressure tending to hold the valve in position for opening the rear end of the cylinder to exhaust and means controlled by the piston for intermittently throwing the valve to its other position for admitting pressure fluid to the rear end of the cylinder.

5. In a drilling apparatus, a pressure fluid actuated percussive motor, a piston reciprocable therein, a striking bar projecting from the piston through one end of the cylinder, and fluid distribution means for actuating said piston including means for continuously admitting fluid pressure to the forward end of the cylinder to act on the reduced area of the piston around the striking bar, a valve for controlling the supply and exhaust of fluid from the rear end of the cylinder, said valve having a central spool for alternately establishing communication of the rear end of the cylinder with the supply and exhaust, a larger spool on one side of said central spool, said spools having adjacent opposed surfaces presenting a differential area to the action of fluid supply pressure tending to hold the valve in one extreme position for opening the rear end of the cylinder to exhaust, and a throwing passage controlled by the piston for

admitting pressure fluid from the cylinder to the opposite side of said larger spool for throwing the valve to its other extreme position for effecting admission to the rear end of the cylinder, and guiding means on said valve on the opposite side of said central spool from the larger spool.

6. In a drilling apparatus, a pressure fluid actuated percussive motor, a piston reciprocable therein, a striking bar projecting from the piston through one end of the cylinder, and fluid distribution means for actuating said piston including means for continuously admitting fluid pressure to the forward end of the cylinder to act on the reduced area of the piston around the striking bar, a valve for controlling the supply and exhaust of fluid from the rear end of the cylinder, said valve having a central spool for alternately establishing communication of the rear end of the cylinder with the supply and exhaust, a larger spool on one side of said central spool, said spools presenting a differential area to the action of fluid supply pressure tending to hold the valve in one extreme position, a throwing passage controlled by the piston for admitting pressure fluid from the cylinder to the opposite side of said larger spool for throwing the valve to its other extreme position, and guiding means on said valve on the opposite side of said central spool from the larger spool, said guiding means constituting a third spool of the same size as the central spool, and a leak passage for relieving the throwing pressure on said larger spool when said throwing passage is closed to said cylinder.

7. In a drilling apparatus, a fluid pressure actuated percussive motor having a cylinder, a piston head reciprocable therein, a striking bar projecting from said head, and fluid distribution means for effecting reciprocation of said piston including a valve having large and small spools, a fluid supply inlet, a passage for conducting live fluid to the front end of said piston, a passage controlled by the smaller spool whereby live pressure fluid communicates with the rear end of said piston, an exhaust passage, a passage leading from said cylinder and controlled by said piston head, said piston controlled passage being adapted to have communication with said exhaust passage through said valve mechanism and to conduct live pressure fluid to one side of the larger spool to move said valve.

8. The combination set forth in claim 7 further characterized in that a transverse surface of said valve is constantly subjected to live fluid pressure.

9. The combination set forth in claim 7 further characterized in that a transverse surface of said valve is constantly subjected to live pressure fluid, and means are provided whereby the actuating fluid from one end of

said cylinder is directed to said exhaust passage by the smaller spool.

10. A pressure fluid motor comprising a cylinder, a piston reciprocable therein, and fluid distribution means for effecting reciprocation of said piston including an inlet passage, a passage for admitting pressure fluid to the front end of said piston from said inlet, means for controlling the supply of fluid for and exhaust of fluid from the rear end of said piston comprising a reciprocable differential fluid distribution valve having a large spool and a reduced spool, a passage controlled by said piston for admitting pressure fluid from said cylinder to one surface of said large spool for throwing said valve in one direction and to connect the rear end of said piston through the valve chest directly with the rear end of said first mentioned passage, and a passage for constantly admitting pressure fluid to the opposite surface of said large spool for throwing said valve in the opposite direction to connect the rear end of said piston with the exhaust.
15. 11. A pressure fluid motor comprising a cylinder, a piston reciprocable therein, and fluid distribution means for effecting reciprocation of said piston including an inlet, means for controlling the supply and exhaust of fluid for the rear end of said piston comprising a reciprocable differential fluid distribution valve having a large spool and a reduced spool, a passage controlled by said piston for admitting pressure fluid from said cylinder to one surface of said large spool for throwing said valve in one direction to connect one end of said piston with the fluid supply, a passage for constantly admitting pressure fluid to the opposite surface of said large spool to throw said valve in the opposite direction to connect the rear end of said piston to the exhaust, and a leak passage for connecting the pressure area at the rear end of said large spool with the exhaust.

45. In testimony whereof I affix my signature.
ELMER G. GARTIN.
